VALVE SAFETY HANDLE

Stephen Matousek and Ulrich H. Koch, Moraga, and
Richard S. Di Gennaro, Berkeley, Calif., assignors to
Whitey Research Tool Co., Emeryville, Calif.

Filed Apr. 29, 1975, Ser. No. 572,751

Term of patent 14 years

Int. Cl. D23—01

U.S. Cl. D23—30

FIG. 1

FIG. 2

FIG. 4

FIG. 3

FIG. 5

FIG. 1 is a perspective view taken from the top and side of a valve safety handle showing our new design;

FIG. 2 is a top plan view thereof;

FIG. 3 is a bottom plan view thereof;

FIG. 4 is an end view thereof; and

FIG. 5 is a side elevational view thereof.

We claim:

The ornamental design for a valve safety handle, as shown.
